UNITED STATES PATENT OFFICE

FERDINAND R. OERTEL, OF BROOKLYN, NEW YORK

PRINTING PRESS

Application filed October 21, 1927. Serial No. 227,633.

My invention relates to improvements in apparatuses for printing on both faces of a succession of separate sheets. My invention consists of the combination with two printing-units, of any suitable or desirable kind, of an interposed sheet-inverter or fly, whereby each successive sheet is printed on one face by the first unit, then inverted by the fly, and then passed forward in the same 10 direction with its unprinted face presented to the action of the second unit. According to my invention, the sheet is not diverted laterally out of its direct line of travel, but is turned heels over head, as it were, by the 15 fly.

The invention is susceptible of embodiment in various forms, and will be best understood by reference to the ensuing description of a preferred form or embodiment of the apparatus and of alternative means for actuating the fly, as illustrated by the accompanying drawings. It is to be understood distinctly, however, that the description and drawings are illustrative only, and are not intended to 25 limit the invention more specifically than as set forth in the appended claims.

In these drawings, Fig. 1 is an elevation, partly in vertical section, which shows diagrammatically the complete apparatus;

Fig. 2 is a side view, on a larger scale, of the fly and one form of means for actuating it, viewed from the opposite side of the complete apparatus illustrated by Fig. 1;

Fig. 3 is a portion of a plan view of the 35 device set forth by Fig. 2; and

Fig. 4 is a face view of another fly-actuating means.

In the right-hand portion of Fig. 1 is indicated the first printing-unit, whose revolvable cylinder is designated 10, the usual reciprocating type-bed for coaction therewith being indicated conventionally at 10'. In the left-hand portion of said Fig. 1 is indicated the second printing-unit, whose revolvable cylinder 11 rotates in synchronism with said cylinder 10, its co-acting type-bed being indicated conventionally at 11'. In the particular form of apparatus indicated, each cylinder 10 and 11 will make two complete revolutions between the instant the cylinder

receives the front edge of a sheet and the instant it receives the front edge of the next sheet. Between these two printing-units is the sheet-inverter or fly, comprising a rockable shaft 12 parallel with the axes of the two cylinders, and a plurality of mutually-parallel fingers 13 carried by said shaft, as best seen in Fig. 3. On the end of the fly-shaft 12 is fixed a gear 14. Adjacent said gear is a lever reciprocable on a fulcrum 15, which is parallel with said shaft 12. One arm 16 of this lever is a sector-gear whose teeth 17, arranged concentrically of the fulcrum 15, mesh with said gear 14. The other arm 18 of said lever is pivotally connected to an actuating-pitman 19, operated as by revolutions of the cylinders. In the arrangement shown by Figs. 1-3, the other end of this pitman is pivotally connected to a wrist-pin 20 carried eccentrically upon a plate 21, preferably mounted for axial adjustment upon a revolvable plate 20', which latter has its axis parallel with the axes of the cylinders 10 and 11, and is rotated at one-half the speed of the cylinders, as by being properly geared to one of them.

Referring to Fig. 2, it will be noticed that the fly-fingers 13, as there indicated in full lines, are in position to receive a sheet coming from the first printing unit; and, when the fly-fingers are in this receiving position, the joint 22 (connecting the pitman and the lever arm 18) is in its position nearest the axis of revolution of the wrist-pin 20. The position occupied by the fly-fingers when delivering the sheet to the second printing-unit (not shown in Fig. 2) is indicated by dotted lines 13'; and when the fly-fingers are in this delivering-position, the joint (connecting pitman and arm 18) is in its position furthest away from said axis, as indicated by dotted lines and the reference numeral 22'. An intermediate position of the fly-fingers and said joint is likewise indicated in Fig. 3 by dotted lines and the reference numerals 13'' and 22''. It will now be understood that each sheet, after being delivered to the first printing unit and receiving the desired printing upon one face, is then carried forward by any suitable or desired means, all as is well

understood in the printing-press art, and will then lie upon the fly-fingers 13, which at that instant are in the receiving-position shown in full lines by Fig. 2; at that same instant 5 also, the rotational movement of the plate 21 causes the wrist-pin and pitman to commence actuation of said sector 16, which causes the fly-fingers to sweep over into the delivering-position 13', thereby inverting the sheet so that its unprinted face will be the one offered 10 to the action of the second printing-unit; and thence the sheet will be carried forward, in well-known manner, to present its unprinted face to the action of the second printing-unit, meanwhile completion of the full 15 revolution of said wrist-pin returns the fly-fingers to their receiving-position.

Each complete revolution of the wrist-pin thus causes one complete to-and-fro swing 20 of the fly-fingers. The wrist-pin will have been properly adjusted, of course, so that the fly-fingers will begin and will end their movements at precisely the proper instants.

The printing of one sheet will require one 25 complete revolution of the cylinders 10 and 11, attended by the completion of the forward movement of the reciprocating printing-beds 10' and 11'. The printing beds must be returned to their initial positions, before the 30 printing of a second sheet can be commenced. This return movement requires the same time as the forward movement, that is, the time for a second complete revolution of the cylinders. In short, there must be two complete 35 revolutions of the cylinders for the printing of each sheet, one revolution for the actual printing, followed by a non-printing revolution for the return of the printing-beds. If, during each complete revolution of the cylinders, the fly-fingers should make one complete 40 to-and-fro swing, they would make one complete swing during a printing-revolution and a second (but non-useful) complete swing during a non-printing revolution, making 45 twice as many swings and therefore moving twice as rapidly as necessary. Consequently, it is preferable to have only one complete to-and-fro swing of the fly-fingers for each two successive complete revolutions of the cylinders. It is clear that this particular co- 50 ordination can readily be attained by mounting the plate 21 with its wrist-pin 20 upon an independent journal of its own, and properly gearing the same to the adjacent cylinder 10, for rotating said plate at one-half the speed of the cylinder.

Where the output of the apparatus is to proceed at only moderate speed, the above-described pitman-actuating means shown by 55 Figs. 1-8 will be sufficient. But where the apparatus is to deliver its output at higher speed, it is preferable to resort to a cam with two curvatures. In high-speed operation, the fly-fingers must make each complete to-and-fro swing within an exceedingly short period

of time; the forward movement, while carrying a sheet, is impeded by the air resistance of the sheet; and, therefore, this forward movement is perforce relatively slow. But the return movement, unimpeded by the sheet, can be sufficiently speeded up so as to compensate for the retardation of the forward movement. In Fig. 4, therefore, is shown a circular cam-plate 23, which is secured concentrically and for rotary adjustment upon a plate 20', in place of the plate carrying the wrist-pin. This cam-plate is provided with a cam-groove 24, whose eccentricity is shown as beginning at a minimum, as at point *a*, and increasing gradually for more than half way (or more than 180°), say 270°, around the face of the plate to a maximum, as at point *b*, and thence decreasing rapidly to the point of beginning at *a*. The cam-groove is so plotted, and the cam-plate is then so adjusted on the revoluble plate 20' that, cooperating with a suitable follower 25, carried by the pitman and guided rectilinearly by a straight groove in a stationary member 26, the gradually increasing eccentricity of the cam will cause the fly-fingers to begin their relatively slow and impeded forward movement at precisely the proper instant, and thereafter the rapidly-decreasing eccentricity will cause the fly-fingers to begin their unimpeded return at precisely the proper instant and to complete the return in a relatively short space of time.

Having thus disclosed my invention, and given full details of its fly-actuating means, 100 but only for the sake of clear illustration, I claim:

1. A printing-apparatus, which comprises, in combination, two printing-units, each of which has a revoluble cylinder and a reciprocal type-bed coacting therewith, an interposed fly having a rock-shaft parallel with the axes of said cylinders, a spur-gear secured to said rock-shaft, a lever having one arm formed into a sector-gear meshing with said spur-gear, a pitman pivoted to the other arm of said lever, and means for actuating said pitman in synchronism with the revolutions of said cylinders.

2. A printing apparatus, which comprises, in combination, two printing-units, each of which has a revoluble cylinder and a reciprocal type-bed coacting therewith, an interposed fly having a rock-shaft parallel with the axes of said cylinders, a spur-gear secured to said rock-shaft, a lever having one arm formed into a sector-gear meshing with said spur-gear, a pitman pivoted to the other arm of said lever, and an eccentric member rotated from one of said cylinders for actuating said pitman.

3. A printing apparatus, which comprises, in combination, two printing-units, one of which has a revoluble cylinder, an interposed fly having a rock-shaft parallel with the axis

of said cylinder, a spur-gear secured to said rock-shaft, a lever having one arm formed into a sector-gear meshing with said spur-gear, a pitman pivoted to the other arm of said lever, and a cam of two curvatures rotated from said cylinder for actuating said pitman and causing said fly to swing forward with relative slowness and to return with relative rapidity.

10 4. A printing apparatus, which comprises, in combination, two printing-units, one of which has a revoluble cylinder, an interposed fly having a rock-shaft parallel with the axis of said cylinder, a spur-gear secured to said rock-shaft, a lever having one arm formed into a sector-gear meshing with said spur-gear, a pitman pivoted to the other arm of said lever, a rotarily-adjustable plate rotated from said cylinder and having a cam of two curvatures, a follower carried by said pitman and located in said groove, and means confining said follower to rectilinear reciprocation, whereby said fly is caused to swing forward with relative slowness and to return with relative rapidity.

25 5. A printing apparatus, which comprises, in combination, two printing-units, each of which has a revoluble cylinder and a reciprocable type-bed coating therewith, an interposed fly having a rock-shaft parallel with the axis of said cylinder, a spur-gear on said rock-shaft, a lever having one arm formed into a sector-gear meshing with said spur-gear, a pitman pivoted to the other arm of said lever, and a revolving eccentric member for actuating said pitman.

40 6. A printing apparatus, which contains, in combination, two printing-units, one of which has a revoluble cylinder, an interposed fly having a rock-shaft parallel with the axis of said cylinder, a spur-gear on said rock-shaft, a lever having one arm formed into a sector-gear meshing with said spur-gear, a pitman pivoted to the other arm of said lever, and a rotating cam of two curvatures for actuating said pitman and causing said fly to swing forward with relative slowness and to return with relative rapidity.

45 7. A printing apparatus, which comprises, in combination, two printing-units, one of which has a revoluble cylinder, an interposed fly having a rock-shaft parallel with the axis of said cylinder, a spur-gear on said rock-shaft, a lever having one arm formed into a sector-gear meshing with said spur-gear, a pitman pivoted to the other arm of said lever, a rotating and rotarily-adjustable plate having a cam of two curvatures, a follower carried by said pitman and actuated by said cam, and means confining said follower to rectilinear reciprocation, whereby said fly is caused to swing forward with relative slowness and to return with relative rapidity.

In testimony whereof I affix my signature.

65 FERDINAND R. OERTEL.
